(57) **CLAIM**

The ornamental design for a plush container as shown and described.

DESCRIPTION

FIG. 1 is a front view of a plush container;
FIG. 2 is a rear view of the plush container illustrated in FIG. 1;

FIG. 3 is a left side view of the plush container illustrated in FIG. 1;

FIG. 4 is a right side view of the plush container illustrated in FIG. 1;

FIG. 5 is a top view of the plush container illustrated in FIG. 1;

FIG. 6 is a bottom view of the plush container illustrated in FIG. 1; and,

FIG. 7 is a front, perspective view of the plush container illustrated in FIG. 1.

The broken lines shown in the figures depict portions of the plush container that form no part of the claimed design.
